AIR CIRCULATING MECHANICAL
REFRIGERATOR

Lonnie C. Montgomery, Whittier, Calif.

Application November 4, 1936, Serial No. 109,089

3 Claims. (CL 62—3)

My invention pertains to so-called mechanical refrigerators in which by some type of refrigerating equipment refrigerator units are utilized located in a sense in separate compartments. 5 These compartments are however provided with means for air circulation between the two compartments.

There are certain disadvantages in mechanical refrigeration, especially as applied to domestic 10 or small sized refrigerators, among which may be mentioned the frosting, that is, freezing of moisture on the cooling coils. As ice itself is a relatively good heat insulator, the efficiency of the heat transfer between the air of the compartment 15 of the refrigerator to the refrigerating liquid in the coils is decreased. It is therefore necessary to remove this ice from the cooling coil periodically. This is termed "de-frosting."

Also, in the mechanical refrigerator during the 20 defrosting operation and the time consumed for this, the refrigerator is allowed to become warm, usually either by stopping the refrigerating unit or by decreasing the refrigerating action so that the exterior of the cooling coil may rise above 25 the freezing point. This allows all of the interior of the refrigerator to become warmed to a temperature considerably above that which is desirable for maintaining the produce or commodities in the refrigerator at a desired refrigerated 30 temperature. Frequently this action causes the spoiling of produce in the refrigerator. Moreover the continuous chilling and warming of certain produce is decidedly disadvantageous. In certain types of commodities this alone causes a 35 spoiling and waste of food products.

Another disadvantage of the usual mechanical refrigeration is the extraction of moisture from vegetables and fruits due to the continuous circulation of the same air in the refrigerator, the drying 40 of this air by freezing or condensing of the moisture on the cooling coil and hence the supply of this moisture to the dry air from the vegetables, fruits or similar commodities. In fact, in the usual mechanical refrigerator it is necessary 45 to make special provision by having separate compartments to retard the drying of vegetable products of various kinds. A further annoyance is developed by the odors of certain products being taken up by other produce in a mechanical 50 refrigerator. This is due in part to the odors being carried by the circulating air, especially by the moisture of the air which in partially condensing on other cool produce causes a transfer of the odor from for instance a product which is 55 quite pronounced as to certain odors, to other products which practically lack a definite odor. Manifestly this is disagreeable. In the ordinary mechanical refrigerator in addition, it is necessary to make provision for a down and an up flow 60 of air in the one refrigerator compartment due to

the cooling action of the cooling coils which ordinarily are placed at the top of the refrigerator so that the chilled air being denser than the warm air descends to the bottom of the refrigerator compartment and the warm air flows up. Sometimes there is a distinct intermingling of this direction of flow which prevents the chilled air reaching the bottommost part of the refrigerator chamber. 5

There are also certain disadvantages of ice refrigerators in that it is necessary to service these quite frequently in order to maintain a large body of ice in the ice compartment, for it is only by maintaining a sufficiently large quantity of ice that a uniform refrigerating temperature may 10 be maintained in the commodity compartments of the ice refrigerator. The ice refrigerator has certain advantages however, in that the melting ice supplies moisture to the air which is continuously circulating in the commodity space and 15 thus fruits, vegetables and the like are not dried out by extraction of moisture therefrom. In addition, the odors of certain produce carried by the vapor of the air are removed from the refrigerator. This is probably due to the warm rising air when 20 coming in contact with the block of ice having a part of its moisture condensed on the block and then this is carried away with the waste water from the melting ice. Due to this action of the 25 water from the melted ice being carried by a drain pipe completely out of the refrigerator, there is no water standing for any material length 30 of time in the refrigerator.

An object and feature of my invention is to overcome many of the disadvantages of the so-called mechanical refrigeration and to incorporate a number of the advantages of the ice refrigeration system. To this end I make the refrigeration and de-frosting automatic and have a definite path established for the circulation of 35 the chilled and the warmed air. In a simple type of refrigerator such as would be suitable for domestic use, I use dual cooling units or cooling coils, these being separated by an insulated partition which partition however, has provision 40 such as openings adjacent the bottom and top for the circulation of air between the two compartments of the refrigerator. The automatic control is such that while one cooling coil is operating for refrigeration, that is, it is cooled to a 45 low temperature, the other coil is allowed to warm up for de-frosting. This develops an air circulation downwardly in one compartment from the chilling coil, the cool air passing through the 50 openings adjacent the bottom of the partition 55 to the other compartment in the refrigerator where such air is warmed by the produce contained therein and by transfer of heat from the exterior of the refrigerator so that the warm air in rising and having a direction of flow around 60

the second cooling coil causes a warming of such coil and hence a de-frosting. This uprising current of air passes through the openings adjacent the top of the partition to the first mentioned compartment.

- Another object and feature of my invention is in the provision for automatically operating one coil as a refrigerating unit and having the other inactive by means of one or more control valves which are operated by one or more thermostats and such valves directing the flow of the refrigerating fluid from the compressor to one or other of the cooling coils located at the upper part of its own compartment of the refrigerator. Provision is made for an outflow of the water melted from the cooling coils so that this does not remain in the refrigerator.
- An advantage of this construction and system of mechanical refrigeration is that at no time will one of the compartments become warmed to a sufficient extent that it would be injurious to the produce contained therein. A positive circulation is developed of the cool air downwardly in one compartment and the warmed air upwardly in the other compartment. This prevents countercurrents of air in the same compartment. In addition, the produce in both compartments is kept from drying out due to maintenance of a proper moisture content in the circulating air in both compartments as manifestly when one cooling coil is being de-frosted, a certain amount of the moisture from the water melting from the ice is taken up by the warm circulating air. Another advantage is that odors are not transferred from one produce to another. It is presumed that these odors are in some manner carried by the circulating air probably by the moisture or water content of the air in the upflowing stream of air in one compartment in which the cooling coil is being de-frosted. If there is excessive moisture in the upflowing air a portion of this will be condensed on the cooling coil being de-frosted and flow out with the water melted from the ice. The vapors carried over to the chilling coil of the first compartment are condensed with the excess moisture forming a coating of ice on the coil which is actively engaged in the refrigerating and chilling. As an automatic switch-over is made in having for instance a first cooling coil operative for refrigeration and the other inoperative for de-frosting, no personal attention is required to this de-frosting action. Moreover, with this type of refrigerator as the bottom of both compartments is the coldest portion, the produce which it is necessary to maintain at a lower temperature than other produce, may be placed in the bottom portions of the two compartments and such produce undergoes very little change of rise and fall of temperature in the de-frosting period of the cooling coils.
- A further characteristic of my invention is that the thermostats for controlling the switch-over of the refrigerating units should be mounted preferably contiguous to these units. As the valve for reversing the flow of the refrigerating fluid is influenced by the warm temperature at the coil being de-frosted, this part of the refrigerator would be the warmest portion thereof.
- It will be understood that the thermostats may be of any suitable type and control the action of the refrigerating fluid valve in any suitable manner which arrangement may be an electrical control or a mechanical control or a combination of both.

My invention does not necessitate particular improvements in the refrigerating appliances per se as most of the types now on the market can be readily adapted for the purpose of this invention and therefore I do not describe the refrigerating equipment in detail except such as is necessary to indicate the reversal of flow of the refrigerating fluid.

My invention is illustrated in the accompanying drawings, in which:

Fig. 1 is a front elevation of a domestic type of mechanical refrigerator equipped with my invention.

Fig. 2 may be considered either a side elevation taken in the direction of the arrow 2 of Fig. 1, the side wall and certain interior parts broken away, or on the section line 2-2 of Fig. 3 taken in the direction of the arrows.

Fig. 3 is an elevation of the interior of the refrigerator with parts broken away and illustrating the refrigerating assembly in a more or less diagrammatic manner.

Fig. 4 is a diagram showing in part the dual refrigerating units or coils and a thermostat control for electro-magnetically controlling a valve forming a communication between the refrigerator fluid compressor or body of compressed fluid and the two cooling units.

Fig. 5 is a diagram showing a mechanical connection for operating the fluid valve.

In my invention I utilize a more or less conventional refrigerator cabinet 11 which is illustrated as having an upper part 12 with a space for a refrigerating machine which may be a compressor alone or with a compressor condenser assembly of the conventional type. The lower part 13 also provides a space for a condenser where this is separate from the assembly with the compressor. A door 14 forms an opening to the interior of the cabinet which has the usual heavy heat insulated walls designated 15. The refrigerator thus provides the usual food storage space having a floor 16 and a series of trays 17. The top wall 18 separates the cooling units and storage space for produce from the upper part 12 having the refrigerating machine such as the compressor and condenser.

In my invention I install a central partition 20 between the bottom 16 and the top 18, this running from the back 21 of the storage compartment to the front 22 which is closed by the door 14. There is a lower air circulating opening 23 and an upper opening 24 adjacent the top 18 for the same purpose. These are shown as slots extending from the back to the front of the storage space for produce. By this arrangement I provide two compartments 25 and 26 on each side of the partition for the storage of produce and to separate the cooling units, that is, the evaporators 27 and 28. These evaporators may be of the usual character and are generally formed of coils of pipe 29 through which the refrigerating fluid is caused to flow in any suitable manner.

In the construction illustrated in the drawings and diagrams a compressor unit 30 is illustrated located in the upper part 12. From this as shown in Fig. 3, a pipe 30' leads downwardly to a condenser unit 38 which is located in the lower part 13. A feed pipe 31 thus from the condenser of the compressor and the condenser assembly discharge through a conventional expansion valve 32 and thence to a two-way shifting valve 33 from which there are feed pipes 34 and 35 leading to the evaporating units 27 and 28.

Each of these units has a flow pipe, 36 and 37, for suction flow direct to the compressor, these being illustrated in Fig. 3 as connected through a T coupling.

5 With my invention I utilize two water pans 40 and 41, each located below the cooling unit in a compartment to receive the water from ice melted off the coils 29 of each unit. A waste water or drain pipe 42 connects to each pan, each pipe 10 having a gooseneck 43 forming an air trap. The drain pipes may discharge completely out of the refrigerator cabinet, the waste water being led away in any suitable manner or if desired they could lead to water receptacles 44 which may be 15 emptied in a conventional manner when desired.

A suitable manner for cutting the cooling units 27 and 28 in and out of refrigerating action is shown particularly in Fig. 4 in which the valve 33 for supplying the refrigerating fluid to either of 20 the cooling units is provided with an operating arm 50 secured to the stem or spindle 51 of the valve 33. This arm is connected by a tension spring 52 attached to one end 53 of the arm and at 54 to a fixed structure of the cabinet. The 25 opposite end of the arm has a slotted yoke 55 in which operates a pin 56 on a transversely moving rod 57. This rod has end portions 58 and 59 which function as movable armatures for the electro-magnetic devices 60 and 61, each of which 30 has a suitable wire winding 62.

The thermostat control designated by the assembly numeral 65 employs two thermostats 66 and 67, one of these being installed in one of the food compartments 25 and the other in the second food compartment 26. For purposes of illustration, these are shown as the diaphragm type but 35 may be of any suitable character. Each thermostat has a plunger or movable end 68 operating a switch lever 69 shown pivoted at 70. Each lever has a switch contact 71 to form a closed circuit with a complementary fixed contact 72. The armature ends 58 and 59 of the rod 57 are provided with insulation 73 and a conducting bar 74 positioned to engage a brush 75 mounted on the 40 fixed structure 76.

45 The electric circuit is illustrated as having a lead 80 connected to a power source, this branching as indicated at 81 and having leads 82 and 83 connecting respectively to the switch arms 69 and thus to the moving contacts 71. From the 50 fixed contact 72 there are electric leads 84 and 85 to one end of each of the windings 62 of the electro-magnetic devices 60, 61. The opposite end of each coil has a connection 86 to its brush 75 and from such brush there is a return lead 87 to ground 88. The source of current supply also 55 has a ground connection.

In the operation of this type of device the over-balance spring 52 always maintains the valve 33 in one of its open positions, that is, communicating from the pipe 31 to one of the cooling units 27 or 28 but it can never form a connection to both of these. In the illustration of Fig. 4 it is 60 presumed the connection is to the cooling unit 27 which thus receives the refrigerating fluid to cause a chilling or refrigerating action of the unit 27. The thermostat 66 at the produce compartment 25 is shown as being cold and having the switch with the contacts 71 and 72 open. The other thermostat 67 is illustrated as being 65 hot or warm with the switch contacts 71 and 72 closed.

70 The action and function therefore in refrigeration is somewhat as follows: Presuming the cooling unit 27 is actively engaged in refrigeration, 75 that is cooling by the flow of the refrigerating

fluid therethrough, this causes a chilling of the air in the left hand compartment 25 (note Fig. 3). This of course cools the air immediately surrounding the cooling unit 27 which becomes denser than the air therebelow and develops a 5 downward circulation of air as indicated by the arrows 90. This air flows through the lower opening 23 as indicated by the arrows 91 entering the warming compartment 26 adjacent the bottom. As the cooling unit 28 of the compartment 26 is out of action, that is, there is no cooling fluid circulating therethrough, the coils of this unit have no chilling action except for the ice which may be on such coils, hence the air in the compartment 26 becomes warmed and 10 develops an upward direction of flow indicated by the arrows 92. The temperature of this air rises the higher up it gets in the compartment 26 and thus a body of comparatively warm air is brought into contact with the cooling unit 28 and 15 melts the ice formed on the coils 29 of such unit. This causes a de-frosting action, the water dripping into the pan 41 and flowing outwardly through the waste or drain pipe 42. The heated air maintains its circulation and passes through 20 the upper opening 24 in the direction of the arrows 93 to the upper part of the compartment 25 contiguous to the cooling unit 27.

As this unit is undergoing a refrigerating action with the refrigerating fluid passing there- 30 through, it is at a low temperature and hence as the warm air passing through the top opening 24 contains moisture, a proportion of this is condensed on the cooling unit 27 depositing in the form of frost or ice. The moisture contact 35 of the warm air has been supplied in part by the melting ice and frost on the cooling unit 28 which is undergoing de-frosting. Of course before this unit is completely de-frosted and is covered with ice, the vapors carried by the upwardly flowing 40 air 92 will be to a certain extent condensed on the melting ice on the unit 28 and a further amount condensed on the unit 27.

The circulation of air continues as shown by the arrows 90, 91, 92 and 93 until the thermostat 67 in the food compartment 26 expands due to its increased temperature and closes its switch having the contacts 71 and 72. During this operation the rod 57 and the armatures 58 and 59 connected thereto occupy a left hand position as shown in dotted lines in Fig. 4. This is a position of rest in which the valve arm 50 could occupy a position reverse of that shown in Fig. 4. There is then an electrical contact between the 45 conducting bar 74 and the brush 75 which brush is associated with the electro-magnetic device 61. 50

Hence an electric circuit is established from the source of power through the leads 83, the switch contacts 71 and 72 on the right hand side, the right hand leads 84 and 85 to the winding 62 of the electro-magnetic device 61, thence through the brush 75 on the right hand side to its contact bar 74. This gives a momentary energizing of this electro-magnetic device 61 developing a movement of its armature 59 and hence of the whole rod 57 and the opposite armature 58 bringing these to the position shown in full lines in Fig. 4 which action breaks the circuit between 74 and the brush 75 on the right hand side thus de-energizing the electro-magnetic coil 60 65 70 75 76 77 78 79 80 81 82 83 84 85 the pipe 31 to the cooling coil 28 and cut off the flow to the cooling coil 27.

Thus the cooling unit 28 is brought into refrigerating action and causes a chilling of the air in the upper part of the compartment 26. This action slowly stops the circulation of air until it is cooled sufficiently to descend in this compartment 26 in a reverse direction to the arrows 92 and flow upwardly in the left hand compartment 10 reverse of the direction of the arrows 90. This action brings warm air into contact with the cooling unit 27 which in the prior action has become coated with ice or frost and it undergoes a de-frosting action and thus melts the ice in the unit 27, the water dropping into the pan 40. When the temperature in the compartment 25 rises to a predetermined value, the thermostat 67 expands and closes its contact switch. Of course manifestly as the compartment 26 cools, the thermostat 67 contracts and opens its switch. The cycle of operations is then repeated at periodical intervals, dependent on the rate of refrigeration of one compartment and the rate of heating of the other.

25 Presuming it is desired to start the refrigerator operating in which both of the chambers are warm, it is immaterial which cooling unit first comes into operation as the over-balance spring 52 will always hold the valve 33 in one of its extreme positions, that is, either feeding the refrigerating fluid to the cooling unit 27 or 28 but not to both at the same time.

In Fig. 5 I illustrate a mechanical arrangement for operating the fluid valve for directing the flow of the refrigerating fluid to one or other of the cooling coils. In this case I show two diaphragm type of thermostats designated 100 and 101, each of which has a plunger 102 connected to the diaphragm and operatively connected to one end of a lever 103 and 104 fulcrumed at 105 on a fixed structure. Flexible cables 106 and 107 lead from these levers passing over change of direction pulleys 108. Each cable has a spring 109 and 110 connected thereto and the springs being attached to a single link 111, such link being pivotally connected to the actuating arm 112 of the valve 33. An over balance spring 113 is connected at one end to a fixed structure and at the other end to the pivot 114 connecting the arm 112 to the link 111.

The operation of this device is substantially as follows: Presuming the arm 112 has been located in a position directing the refrigerating fluid through the pipes 31 and 34 to the refrigerating unit 27, this allows the thermostat 101 to become heated, giving a movement of the lever 104 from its tilted up position to a downwardly inclined position, thus exerting a tension on the cable 107 and through the spring 110 and the link 111 moving the arm 112 past the center so that the over balance spring 113 will give a quick action in finally shifting the valve. It will be understood that when the refrigerating unit 27 is being cooled that the diaphragm in the thermostat 100 collapses or retracts, thus positioning the lever 103 in the position shown in Fig. 5 and slackening the cable 106 so that as soon as the cable 107 develops a tension there is no difficulty in actuating the arm of the valve. As soon as the valve is moved to the position shown in full lines in Fig. 5 the refrigerating fluid is directed through the pipes 31 and 35 to the refrigerating unit 28 causing this to become chilled. The thermostat 101 thus being in a cooling compartment retracts, easing the tension on the cable 107

and the thermostat 100 in the compartment which is warming up expands and develops a tension on the cable 106. If for any reason on account of for instance the refrigerator door being open, both of the thermostats are heated 5 and expanded, this would exert a tension on both cables 106 and 107 and on their springs 109 and 110, but the over balance spring 113 has sufficient tension to always maintain the arm 112 in one or other of the open valve positions so that one 10 refrigerating unit at a time is functioning.

Important characteristics of my refrigerator and method of refrigeration may be defined as follows, referring particularly to Fig. 3. In this case the refrigerating unit 27 is presumed to be 15 operating, that is, actively refrigerating and thus cooling the air in the compartment 25. The air chilled by passing over and in close contact with the refrigerator unit 27 becomes denser and develops a downward flow in this first compartment 20 25. This causes a cooling of the products in such compartment of the whole refrigerating space. It is well known that many of the articles of food kept in a refrigerator give off various odors and other products absorb such odors giving a dis- 25 agreeable combination of tastes to various foods. These odors are carried by the moving air in the refrigerator and to a certain extent by the vapor or water content of such air. The refrigerating unit which is in operation tends to freeze the 30 moisture out of the air passing over such unit and thus condenses the moisture in the form of frost on the active cooling unit. This incidentally to a certain extent, dries the air.

While the refrigerant is passing through the 35 cooling unit 27 and thus is actively engaging in refrigerating operation, the flow of refrigerant through the other unit 28 is stopped. Therefore this unit is inactive. Hence it has no active refrigerating function in the second chamber 26 40 separated from the first by the partition 20 which has the opening 23 at the bottom and the openings 24 at the top. Therefore the air in the compartment 26 becomes warmed. Also there is a positive downward circulation in the compartment 25 which combined with the heating of the air in the compartment 26 produces the upward flow of air in this second compartment. The downward and upward direction of the air flow is indicated by the arrows 90 and 92, the transfer of air at the bottom by the arrow 91 and the reverse transfer at the top by the arrow 93. The relatively warm air flowing upwardly in the compartment 26 carries various odors from the produce in the refrigerator. This upward circulation is in the path of the drip of water from the inactive refrigerating unit 28 and as the temperature of this unit rises the frost on such unit melts, causing a water drip to the pan 41 and the air flowing upwardly is brought in intimate 55 contact with the thin film of water on the inactive unit 28. This water absorbs a considerable amount of the odors of the various foods in the refrigerator and as such water flows into the drip pan 41 it is carried by the waste or 60 drain pipe 42 entirely out of the refrigerator.

As the air in the unrefrigerated compartment 26 becomes warm and thus lighter and flows upwardly, it is able to carry more moisture than the colder air. A certain amount of this moisture is carried over through the upper openings 24 and comes into direct contact with the active refrigerating unit 27. This causes the condensing in the form of frost or moisture on the unit 27 again causing a cooling of the air passing over 70

this unit and continuing the downward flow of chilled air in the direction of the arrow 90. It will thus be seen that due to the intimate contact of the air flow with the chilling refrigerator unit and with the inactive unit, that a great deal of the odors from the food products are carried by the water melting from the warming unit to the drip pans and hence out of the refrigerator.

However the air in its circulation is brought 10 into the intimate contact with the water drip from the cooling unit from which the ice or frost is melting. Thus there is always a desirable moisture contact in the air, thus materially restricting the amount of moisture extracted from 15 food products. Hence with my refrigerator I overcome some of the objections to so-called mechanical refrigeration by eliminating the extraction of moisture from such food products and hence their shrinkage.

20 A characteristic of my invention also resides in the thermostat control. For instance when the air in the second compartment 26 acquires a sufficiently high temperature, this however being below the point at which food products would 25 tend to spoil, the thermostat in such warm compartment is operated and controls the switching of the flow of the refrigerant from for instance the unit 27 to the unit 28, causing this to become active as the refrigerating unit, thereby 30 chilling the air in contact with this unit 28. Manifestly in the early stages of this unit 28 coming into operation, the air flowing upwardly is brought in intimate contact with such unit and becomes chilled, this on the increase of density 35 first causes a stoppage of the flow of air as indicated by the arrows 90 and 92 and then reverses the flow so that the air flows downwardly in the compartment 26 and upwardly in the compartment 25. The action is then reversed, the warm 40 air passing over the inactive unit 27 causes a melting of the frost on such unit, the forming of a film of water and this water dropping into the pan 45 and then being discharged by the drain pipe of the refrigerator. The air in this movement is thus brought in intimate contact with the 50 water drip and the water in the pan, thus removing odors carried by the air but still maintaining a sufficient degree of humidity in the air to restrict the drying out of produce in the refrigerator. As the cycles are repeated, the thermostats 55 each acting when they become heated to a predetermined degree, to develop the automatic switching of the flow of the refrigerant from one refrigerating unit to the other and therefore no personal attention is required to direct or control the flow of air in the two compartments of the whole refrigerator.

Various changes may be made in the details of 60 the construction without departing from the spirit or scope of the invention as defined by the appended claims.

I claim:

1. In a refrigerator, the combination of a refrigerator cabinet having a refrigeration space, a vertical partition separating said space into two refrigeration compartments, said partition having openings adjacent the top and bottom for circulation of air between the compartments, a refrigerating unit in the upper portion of each compartment, each unit being thus separated by

the partition, each unit having a cooling coil, a pipe having a valve for the flow of refrigerating fluid and a connection from the valve to each coil, means to operate the valve to direct the refrigerating fluid to one coil and to cut off the flow of such fluid to the other coil whereby such latter coil is permitted to warm while the coil to which the fluid is directed develops a refrigerating action whereby a downward flow of cooled air is developed in the compartment in which the refrigerating fluid is operating and a warm current of air flows upwardly in the other compartment, such warm air being adapted to melt ice formed on the inoperative cooling coils.

2. In a refrigerator the combination of a refrigerator cabinet having a partition forming two compartments with connections at the top and bottom of the partition for transfer of air, each compartment having means to contain produce to be refrigerated and each compartment having a refrigerating unit in its upper portion, each refrigerating unit being adapted to collect a coating of frost or ice, a water collecting means positioned to collect the water dripping by gravity from the melting frost or ice on each refrigerator unit, means to operate a first refrigerator unit and maintain the second unit inactive whereby the air in the first compartment becomes refrigerated and develops a downward flow, the air in the second compartment being adapted to become heated and develop an upward flow, there being a transfer of cold air from the first to the second compartment at the bottom and a transfer of warmer air from the second to the first compartment at the top, the said refrigerating units being positioned in the path of the flow of air and the water drip collecting means being positioned whereby the water from the melting frost or ice of a refrigerating unit is brought into intimate contact with the flowing air, the upwardly flowing air in the second compartment being adapted to melt the frost or ice from the second refrigerating unit, the first refrigerating unit being adapted to condense and to freeze moisture from the air transferred at the top of the partition from the second to the first compartment.

3. In a refrigerator, the combination of a refrigerator structure having a cooling space, a separating means forming two cooling compartments in said space, with a connection for interchange of air at the top and bottom of the separating means, a refrigerating unit in the upper part of the cooling spaces and on opposite sides of the separating means, the refrigerating units being adapted to provide an ice surface exposed to air, means to collect the drip of water from each refrigerating unit and to discharge such water outside of the refrigerator structure, one of the refrigerating units being adapted to refrigerate the air and to develop a downward flow of air on one side of the separating means, and an upward flow on the other side of the separating means when the second refrigerating unit is idle, the second said refrigerating unit being positioned whereby the upwardly flowing air contacts the ice surface of the second refrigerating unit and melts the ice thereon, the water from the ice dripping into water collecting means, the water collecting means being positioned in the air stream.

L. C. MONTGOMERY.
